CAR TRUCK

Howard D. Taylor, Reading, Pa., assignor to Flexible Truck Corporation, Reading, Pa., a corporation of Delaware

Application September 21, 1931, Serial No. 563,930

8 Claims. (CL. 105—188)

The present invention relates to railway car trucks and seeks to provide an improved construction particularly adapted for a six-wheel truck and in which, while rigid side frames are employed, the parts are connected and arranged to provide flexibility and thereby relieve the strains on the truck structure when in use.

The invention consists in the features of improvement hereinafter set forth, illustrated in the preferred form in the accompanying drawings, and more particularly pointed out in the appended claims.

In the drawings:

Fig. 1 is a partial plan view of the improved truck.

Fig. 2 is a detailed section on the line 2—2 of Fig. 1.

Fig. 3 is a detailed section of one of the cross bolsters taken on the line 3—3 of Fig. 4.

Fig. 4 is a side elevation with a portion of the side frame shown in longitudinal section.

Fig. 5 is a sectional view taken in part in the plane of the truck wheels and in part on the central longitudinal plane of the truck.

Fig. 6 is an end view.

Fig. 7 is a cross section partially on the center line of the truck and partially through one of the cross bolsters.

The truck is provided with separate rigid side frames 10, each provided with pedestal jaws 11 preferably formed integral therewith, and within which the journal boxes 12 are mounted in the usual manner for relative vertical movement. The journal boxes engage the journals of the axles 13 which carry the wheels 14. The upper edge of the side frame is substantially horizontal and it is provided between the pedestal jaws with depending truss-shaped portions 15, provided with openings for receiving the ends of a pair of cross bolsters 16 and bolster supporting springs 17.

Each side frame is preferably formed of a single, integral, chambered or hollow casting and comprises spaced inner and outer side walls 18 connected at their upper and lower edges by transverse webs 19 and 20. Transverse webs 21 between the inner and outer side walls surround the bolster openings and provide seats 22 for the bolster springs and guides 23 for the ends of the cross bolsters. Other transverse webs 24 between the side walls form the inner walls of the pedestal jaws. The side walls above the bolster openings and above the pedestal jaws are provided with heavy reinforcing beads 25 and 26. The latter are arched as shown and merge into

the downwardly inclined arms of the truss-shaped portions 15.

The side frames are supported from the wheel axles by equalizing means including supporting springs. As shown, equalizer bars 27 are disposed within the upper hollow portions of the side frames and are fulcrumed thereto by means of heavy pivots 28. The ends of the equalizer bars rest upon coiled springs 29 which in turn are carried by the journal boxes. The inner arms of 10 the equalizer bars 27 are twice the length of the outer arms thereof to properly equalize the load on the wheel axles.

The equalizer bars arranged in the upper hollow portions of the side frames extend over the 15 bolster openings, and this arrangement affords ample height for heavy springs 29 by which the side frames are supported from the wheel axle. Also, this arrangement of the equalizing means and the deep, truss-shaped portions 15 of the 20 side frames, afford ample room for large bolster openings and the heavy bolster-supporting springs 17, such as required for the heavy loads usual in modern practice. At the same time the side frames are compact both in length and 25 height and ample clearance is provided.

The cross bolsters 16 are provided at their ends with shoulders 30 and lugs 31 (see Fig. 1) which interlock with the column guides 23 on opposite sides of the upper portions of the bolster openings 30 in the side frames. The bolster ends are adapted to be inserted through the enlarged lower portions of the openings and are held in proper position by the springs 17. The cross bolsters thus hold in the side frames in proper spaced relation 35 and flexibly connect the same in a manner permitting considerable independent vertical movement thereof. The side frames are also flexibly connected at their ends by cross bars 32 which extend between outwardly and inwardly projecting offset portions 33 at the ends of the side frames. As shown in Fig. 6, each bar 32 is connected to the one side frame by a horizontal pivot 34 and extends within a pocket formed in the projection 33 on the other side frame. 45 A spring 35 arranged within this pocket extends between a nut 36 and the inner end wall 37 of the pocket to flexibly connect the side frame and cross bar 32. As shown, the bar is provided with a collar 38 which engages the end wall 50 37 and preferably the engaging faces of these parts are curved as indicated in Fig. 6.

A center bolster 39 is disposed above the intermediate wheel axle and between the side frames and is supported from the cross bolsters by in- 55

clined hanger links 40 (see Fig. 7) so that the center bolster is movable transversely to a limited extent relative to the other parts of the truck. This center bolster comprises arched end sections 41 of hollow box sections having offsets 41' for engaging the cross bolsters and maintain the same in parallel relation. Arms 42 at the lower ends of the end sections 41 extend beneath the cross bolsters and are provided with pockets for receiving the lower ends of the hanger links 40. Pivot pins 43 extend through the lower ends of the hangers and through the side walls of the pockets or openings in the arms 42. At the centers of the arched end portions 41, they are provided with upwardly and outwardly extending parts 44 which form or provide seats for suitable side bearings. The intermediate portion of the center bolster comprises a center bearing 45 of usual form and spaced inner and outer side walls 46 and 47. The inner side walls 46 are vertically disposed and are provided with horizontal stiffening flanges 48 at their lower edges and the outer side walls 47 are inclined downwardly and are substantially tangent to the curved centers of the end portions of the center bolster. Also, these outer side walls are provided at their lower edges with vertically disposed stiffening webs 49. The inner and outer side walls 46 and 47 and their stiffening flanges or webs 48 and 49 extend between and are cast integral with the arched end portions.

The cross bolsters 16 are each formed of a single integral casting and as most clearly shown in Figs. 3 and 7 are of hollow box section having top, bottom and side walls. They are provided with longitudinally extending, vertically disposed stiffening webs 50 extending between the top and bottom walls, portions 51 of which are spaced apart to form pockets or openings 52 through which the hanger links 40 extend. The pocket forming walls 51 extend between the top and bottom walls of the bolster and are preferably connected to the side walls by stiffening ribs 53. Also, the top and bottom walls opposite the pockets are preferably increased in thickness as indicated by dotted lines in Fig. 7. At the upper ends of the pockets the bolsters are provided with upwardly projecting ears 54 which receive the upper ends of the hanger links 40 and through which the hanger pivots 55 extend.

The upper portions of the side frames are provided at their ends and above the bolster openings with brackets or offsets 56 and 57 that are preferably integral with the side frames. Brake hangers 58 are pivotally connected to the end offsets 56 and intermediate brake hangers 59 are pivotally connected to the offsets 57 and extend downwardly through openings 60 (see Figs. 5 and 7) formed in the cross bolsters adjacent their ends. Preferably, as shown, the portions of the top and bottom walls of the bolsters are thickened adjacent the openings.

The hangers support brake heads 61 which are preferably connected by brake beams 62. The brake hangers are disposed in the planes of the wheels and brake levers 63 disposed inside of the wheels are connected to the brake beams. The brake levers on opposite sides of each wheel are connected by pull rods 64 and those on opposite sides of each cross bolster are connected at their upper ends by pull rods 65 and these rods are engaged by supporting and guiding rollers 66 mounted on the offsets 57 of the side frames. Spring straps 67 fixed to the bottom walls of the cross bolsters extend beneath the brake beam

62 and engage the edges thereof adjacent the wheels so that they tend to hold the shoes out of contact with the wheels. These straps also serve as safety supports for the brake beams.

Changes may be made in the details set forth without departure from the scope of the invention as defined in the appended claims.

I claim as my invention:

1. A six wheel truck comprising separate rigid side frames, equalizers fulcrumed on the side frames and supported at their ends on the wheel axles, cross bolsters spring supported by and detachably interlocked with the side frames for spacing and flexibly connecting the side frames in a manner permitting their independent vertical movement, and a center bolster carried by the cross bolsters and maintaining the same in parallel relation and having a limited movement relative thereto transversely of the truck, substantially as described. 20

2. A six wheel car truck comprising wheel axles, rigid side frames having pedestal jaws for each wheel axle and intermediate bolster openings, equalizing spring means for supporting the side frame from the wheel axles, cross bolsters 25 detachably interlocked with said bolster openings, and spacing and flexibly connecting the side frames in a manner permitting their independent vertical movement, bolster supporting springs in the lower portions of said openings, a center bolster interposed between and maintaining the cross bolster in parallel relation, and hanger links for supporting the same from the cross bolsters, substantially as described.

3. A six wheel truck comprising wheel axles, 35 separate rigid side frames having pedestal jaws for each wheel axle and intermediate truss-shaped portions provided with bolster openings, equalizers fulcrumed on said side frames extending over the bolster openings and spring supported on the wheel axles, bolsters detachably interlocked with the bolster openings and spacing and flexibly connecting the side frames in a manner permitting their independent vertical movement (bolster supporting springs in the lower portions of said openings, and a center bolster mounted for transverse movement on the cross bolsters and maintaining the latter in parallel relation, substantially as described. 45

4. A six wheel car truck comprising separate 50 rigid side frames, equalizer means including supporting springs for supporting the side frame on the wheel axles, cross bolsters and end bars flexibly connecting the side frames and a center bolster carried by the cross bolsters and mov- 55 ably relatively thereto transversely of the truck.

5. A six wheel car truck comprising separate rigid side frames provided with pedestal jaws and intermediate truss-shaped portions provided with bolster openings, spring supported cross-bolsters 60 and end bars flexibly connecting the side frames, and a centre bolster flexibly mounted on the cross bolsters.

6. In a six-wheel car truck, a rigid cast metal side frame provided with pedestal jaws and intermediate truss-shaped portions provided with bolster openings, the side frame having inner and outer side walls, transverse webs at its upper and lower portions and transverse webs about the bolster openings forming spring seats and bolster guides, and equalizer bars fulcrumed in the portions of the side frame between the inner and outer side walls thereof and extending over the bolster openings and pedestal jaws, substantially as described. 75

7. A rigid cast metal side frame for six wheel trucks having integral pedestal jaws and intermediate truss-shaped portions provided with openings for cross bolsters and bolster springs, the side frame having spaced inner and outer walls connected by transverse webs at its upper and lower edges and extending about the bolster openings and integral inwardly offset portions at its ends and directly above the bolster openings for supporting brake hangers, the upper portion of the side frames being arranged to receive fulcrumed equalizer bars with the latter disposed between the inner and outer side walls thereof and extending over the bolster openings and pedestal jaws, substantially as described. 5
8. A six-wheel car truck comprising wheel axles, separate hollow cast metal side frames having pedestal jaws and intermediate portions provided with bolster openings, equalizer bars disposed within the upper portions of the side frames and fulcrumed thereon, said bars extending over the bolster openings and being spring-supported on the wheel axles, two transverse bolsters detachably interlocked with the bolster openings and flexibly connecting and spacing the side frames, bolster-supporting springs in the lower portions of said openings, and a center bolster mounted for transverse movement on the cross bolsters and arranged to engage and maintain the latter in parallel relation, substantially as described. 10 15
